 tion of Illinois

Application March 14, 1940, Serial No. 323,845

6 Claims. (Cl. 299—120)

This invention relates to an improved nozzle and more particularly to a spray nozzle which is suitable for use in spray drying liquid materials such as milk, eggs, etc.

In my co-pending application Serial No. 273-311, filed May 12, 1939, I have described a novel nozzle construction which produces a desired wide angle cone of such material to be dried. The nozzle there described presents the least resistance to the flow of materials through it and at the same time imparts a maximum of rotational movement to the particles as they leave the nozzle. The nozzle attains this desired end by providing an intermediate rotating zone where the forwardly moving materials are caused to rotate prior to their being passed inwardly to the whirl chamber adjacent to the nozzle aperture. In this construction the materials coming forwardly within the nozzle are first conducted through inclined channels or slots which cause the material to rotate in the annular chamber of the relatively large diameter, and are then conducted through inclined channels or slots into the whirl chamber which is of relatively small diameter.

It is essential that said nozzle be assembled and maintained so that the center of the whirl chamber is in line with the center of the aperture in the nozzle plate. In practice, it is extremely difficult to assemble this structure so that the center of the whirl chamber and the center of the aperture are on the same longitudinal axis. I have found, however, that any change in the centering relationship between the aperture and the whirl chamber causes the angle of cone of the sprayed material to change and the desired maximum contact is not obtained. I have also found that slight changes in the said centering relationship cause a major portion of the spray to be thrown to one side or another of the cone of spray, which has the effect of producing a great variation in particle size. Such a variation prevents uniform drying results.

An important object of this invention is to provide a construction which will permit and attain exact alignment of the center of the aperture in the nozzle plate with the center of the whirl chamber. In my improved construction a means is provided which engages the nozzle plate and also a wall of the body member containing the whirl chamber so that the wall of the whirl chamber will be disposed concentrically with the aperture in the nozzle plate.

As a more specific feature of my invention, the center of the whirl chamber is assembled and held

in exact alignment with the center of the aperture in the nozzle plate by means of a ring, or annular wall, which fits about a shoulder in the transverse wall of the channeled body member and encloses the intermediate rotating zone and is concentric with said zone and with the whirl chamber. The said ring is also removably fitted into a recess in the nozzle plate which is concentric with the aperture therein. Therefore, when the structure is assembled, the aperture and the ring member and the whirl chamber will all be in concentric relationship and materials passing through the nozzle structure will issue from the aperture with the optimum cone angle of spray, and with more uniform size of the particles distributed in the spray.

The said ring is a short, hollow cylindrical body of any suitable material and it may, if desired, be fitted with slots or channels on one end to conduct materials forwardly through the nozzle structure and to correspond with the set of channels in the transverse wall of the body member which impart the first rotation to the material being sprayed. These slots are not an essential feature of the device however and the nozzle structure will operate well without such slots. I have found that the use of said ring member permits obtaining and maintaining the desired rate of flow and of the desired rotation of the liquid and furthermore enables me to obtain the correct concentric relationship between the nozzle aperture and the whirl chamber so that I am able to obtain a wide angle cone of sprayed material, bringing about maximum contact between the particles to be dried and the drying medium. These and other advantages will be more thoroughly understood in connection with the following detailed description as illustrated by the accompanying drawing in which:

40 Figure 1 is a cross sectional view of the nozzle completely assembled, the section being taken along its longitudinal axis;

45 Figure 2 is a perspective view of the body member for guiding the flow of materials within the nozzle;

Figure 3 is a perspective view of the nozzle plate; and

Figure 4 is a perspective view of the ring member.

50 As illustrated in the drawing, A designates a casing or enclosure at the front of which is the disk C. B designates the body member or structure for guiding the flow of materials within the nozzle and D designates the ring, or cylindrical, member for centering the assembly.

The casing A includes the cylindrical wall 1 threaded at both ends. At its rear end the wall 1 is connected to the supply conduit 2 by means of the connector 3 which is adapted to screw over the wall 1 to tighten the shoulder 4 of the supply conduit against the flange 5 extending inwardly of wall 1, the washer 6 being interposed between the shoulder and the flange. At the front end of wall 1 the connector 7 is employed to tighten the disk or forward wall C, carrying the ring member D, against the front of wall 1, the washer 8 being interposed between the disk and the front of the wall. It is understood that any suitable means may be used to secure the nozzle wall to the conduit at the rear and to the disk at the front.

The disk or forward wall C, is provided at its center with aperture 9, preferably countersunk at the interior surface of the disk with annular recess 10. The countersunk opening permits the rotating mass to become focused on the center of the aperture and presents abrasion and wearing away of one side or the other of this opening and thereby maintains the desired centering relationship. Annular channel 10 is recessed into the interior surface of disk C, concentric with aperture 9, and is wide enough to accommodate ring member D.

Structure B includes outwardly extending wall 11 of circular periphery which fits snugly into casing 1, said wall having a front annular recess 12 suitable to receive the rear edge of ring D. In the wall 11 are four slots 13 which are disposed at spaced positions about wall 11 and are each inclined in the same direction with respect to the longitudinal axis of the nozzle. Although in the nozzle illustrated these slots are four in number, other numbers of slots may be used.

The structure B also includes a forwardly protruding annular wall 14, the end of which abuts disk C. The interior of wall 14 forms the wall of the cylindrical whirl chamber 15. At spaced positions about the circumference of wall 14 are the slots 16 which extend through the wall 14 and open tangentially into the whirl chamber 15. A suitable screw member 17 is disposed axially of structure B and has its forward end extended to form the rear wall of whirl chamber 15. This screw is bound in position by nut 18 and lock washer 19. The body member B should be held forwardly against disk C and in the present construction this is done by means of spring 20.

The ring member D has the same outside diameter as wall 11 and fits snugly against the inside of casing 1 and its interior wall, which extends forwardly from wall 11, forms the outer wall of the intermediate rotating zone, or annular chamber 21. When the nozzle is assembled, the rearward end 22 of ring D abuts shoulder 12 of body member B and the forward end 23 fits into annular recess 10 of disk C. As shown, rearward end 22 is fitted with slots 24 which correspond to slots 13 of wall 11 of body member B and, when assembled, are continuous with said slots 13. There are four of slots 24 shown but the number may be greater or less, depending upon the number of slots which it is desired to have in wall 11, or there may be no slots in ring member D corresponding to the slots in wall 11, in which case the assembled nozzle will also operate satisfactorily. The ring D may be of any suitable material, preferably of a hard metal or alloy, such as bronze, since the rotation in the intermediate rotating zone creates a substantial

abrasive action tending to wear away the inner surface.

In assembling this nozzle structure, the ring member D is fitted into annular recess 10 of disk C so that it is then in concentric relationship with aperture 9. Body member B is then placed so that end 22 of ring D abuts shoulder 12 and the periphery of circular wall 11 is continuous with the exterior wall of ring D. Thereupon, 10 whirl chamber 15 and annular chamber 21, are also in concentric relationship with aperture 9 and the desired cone angle will be obtained in the spraying operation.

In assembling a spray nozzle of the type in 15 which the whirl chamber communicates with an aperture in the disk it is important that the central axis of the whirl chamber be in alignment with the aperture and in practice it is difficult to attain this end. It has been necessary to accomplish this result by trial and error, by assembling the nozzle structure and trying out its 20 operation, then dismantling and adjusting the relationship of the parts upon re-assembling. Frequently a large number of such trials have 25 been necessary before the correct alignment was obtained. I have overcome these difficulties by means of my invention which enables me to obtain the desired alignment of the central axis of the whirl chamber with the aperture immediately 30 upon assembling the nozzle structure.

The foregoing detailed description has been given for clearness of understanding only, and no unnecessary limitations should be understood therefrom, it being understood that many 35 changes may be made in the details of construction without departing from the spirit of the invention.

Having thus described my invention, what I claim is:

1. A spray nozzle comprising a casing having a cylindrical interior, a disk secured to the forward end of said casing having an aperture at its center aligned with the central axis of said cylindrical interior and having an annular recess in its 45 inner surface concentric with said aperture, a body member within said casing having a transverse wall extending substantially to the interior surface of said casing and having a front annular recess concentric with the central axis of said 50 body member, said body member having inclined channels extending through said wall to impart a rotating motion to materials passing through them, said body member having also a forwardly extending annular flange of lesser diameter 55 than said wall and having its central axis aligned with said aperture, said annular flange containing channels which lead tangentially therethrough, a ring member having its rearward edge engaged in said front annular recess and having 60 its forward edge fitting into the annular recess in said disk, said ring providing the outer wall of an annular chamber extending about said annular flange, and means for holding said annular flange tightly against said disk to form a closed 65 whirl chamber communicating with said aperture.

2. A spray nozzle of the character set forth comprising a cylindrical casing, a forward wall containing an aperture, a body member in said casing for guiding the flow of material therethrough and having a rearward transverse wall containing inclined channels to impart a rotating motion to materials passing through said channels, said body member having a whirl chamber at its forward end communicating with

said aperture and an annular chamber about said whirl chamber, and a ring member having its rearward edge in centering engagement with said transverse wall and having its forward edge in interlocking engagement with said forward wall, said ring member forming a wall of said annular chamber also having inclined slots adapted to conduct materials forwardly through the nozzle, the side walls of said slots being in continuous relationship with the side walls of the inclined channels in said transverse wall of said body member.

3. A spray nozzle of the character set forth comprising an enclosure containing a body member for guiding the flow of materials therethrough and containing a chamber at its forward end for receiving rotating materials, a ring member in centering engagement with said body member and extending longitudinally of the enclosure, and providing the outer wall of said annular chamber and a forward wall containing an aperture communicating with said chamber, said forward wall having also an annular recess concentric with said aperture and adapted to receive the forward end of said ring member to maintain the central axis of said whirl chamber in alignment with said aperture.

4. A spray nozzle of the character set forth comprising an enclosure containing a body member for guiding the flow of materials therethrough and having a whirl chamber at its forward end, a forward wall containing an aperture communicating with said whirl chamber, said body member having a rearward transverse wall containing inclined channels to impart a rotating motion to material passing through said channels, and a ring member having its rearward edge in centering engagement with said transverse wall and having its forward edge removably engaging

said forward wall to maintain the central axis of said whirl chamber in alignment with said aperture, said ring member providing the outer wall of a chamber within the enclosure for receiving the rotating material.

5. A spray nozzle of the character set forth comprising an enclosure containing a body member for guiding the flow of materials therethrough and containing a whirl chamber at its forward end and an annular chamber about said whirl chamber, a ring member in centering engagement with said body member and extending longitudinally of the enclosure, said ring member providing the outer wall of said annular chamber, and a forward wall containing an aperture communicating with said whirl chamber, said forward wall having an annular recess concentric with said aperture and adapted to receive the forward end of said ring member, whereby a wall of said ring member frictionally engages said forward wall.

6. A spray nozzle of the character set forth comprising an enclosure containing a body member for guiding the flow of materials therethrough and having a chamber at its forward end, said body member being equipped with means for imparting a rotating motion to material passing through the same and into said chamber, a forward wall containing an aperture communicating with said chamber, and a ring member having its rearward edge in centering engagement with said body member and having its forward edge in interlocking engagement with said forward wall to maintain the central axis of said chamber in alignment with said aperture, said ring member providing the outer wall of said chamber.
